Attorney.

UNITED STATES PATENT OFFICE.

JOHN J. KENNEY, OF PITTSBURGH, PENNSYLVANIA, ASSIGNOR TO BEST ELECTRIC COMPANY, OF PITTSBURGH, PENNSYLVANIA, A CORPORATION OF DELAWARE.

SEPARABLE ATTACHMENT-PLUG.

1,341,468.

Specification of Letters Patent. Patented May 25, 1920.

Application filed July 23, 1915. Serial No. 41,585.

To all whom it may concern:

Be it known that I, JOHN J. KENNEY, a resident of Pittsburgh, in the county of Allegheny and State of Pennsylvania, have invented a new and useful Improvement in Separable Attachment-Plugs, of which the following is a specification.

This invention relates to separable attachment plugs, such as are used for making connection from a portable lamp, electric iron or other device or mechanism to a lamp socket or other similar source of current. The object of the invention is to provide a separable plug embodying the usual body member and cap which, when coupled to each other, are positively locked in a manner to prevent accidental separation thereof. A further object of the invention is to provide a separable attachment plug whose members are locked together and can be readily freed from connection to each other when coupled. A further object of the invention is to provide a separable attachment plug whose members may be coupled to each other in the usual manner but are arranged to be positively locked to each other and are unlocked by slight motion of one part relative to the other. A further object of the invention is to provide an attachment plug having an end contact member of simple construction and providing good electrical connection to its spring contact for making connection to one of the terminals.

Further objects of the invention are in part obvious and in part will appear more in detail hereinafter.

In the drawings, which illustrate one embodiment of the invention, Figure 1 is a longitudinal sectional view showing the parts coupled; Fig. 2 is a cross section on the line 2—2, Fig. 1; Fig. 3 is a view corresponding to Fig. 1 and showing the fixed terminals disengaged or unlocked from their spring contacts; Fig. 4 is a cross section on the line 4—4, Fig. 3; Fig. 5 is an end view of the cap uncoupled from the body; Fig. 6 is a cross section on the line 6—6, Fig. 5; and Figs. 7 to 10 are detail views of the spring contacts.

The plug shown in the drawings comprises the usual body member 1 attached to which is a threaded shell 2 to be screwed into the lamp socket, and a cap 3 to be coupled to said body member.

The body 1 and cap 3 are made of any suitable nonconducting material, such as

hard rubber, porcelain, fiber, composition, or other similar material.

The cap 3 carries two stationary terminals 4 and 5, which project from said cap and are adapted to enter openings 6 and 7 in the body member 1, so that the cap and body member are connected by a relative longitudinal movement in the usual manner. The stationary terminals 4 and 5 are flat bars or strips of metal having their outer ends bent laterally, as at 8, and molded into or otherwise attached to the material of the cap 3 so as to permanently secure them thereto. The cap also has cavities 9 on its inner face to receive a lateral wing 10 of each terminal 65 into which is threaded a screw 11 for securing the cord terminals thereto. The cord terminals are attached to the fixed terminal members 4 and 5 of the cap when said cap is disconnected from the body member, as will 70 be readily understood.

When the cap and body are assembled in the manner shown in Fig. 1, the stationary terminals 4 and 5 make electrical connection with contacts 12 and 13 carried by the body member and formed of thin sheet metal having sufficient resiliency to give them a spring action. One of said contacts, marked 12, has a laterally extending wing 14 lying flat against the center of the end 80 portion of the body member, a portion of said wing being punched and bent out to form an opening to receive the securing member 15 and a tongue 16 lying at one side 85 of the same. The securing member 15 is a metal bar or rod having a transverse opening 17 through its inner end, said bar being molded into the material of the body member 1 and permanently secured thereto by said material flowing through the opening 95 17. The opening in the wing of the contact 12 is made slightly smaller, if anything, than the bar 15, so that it is forced over said bar with a driving fit, giving a good contact between the bar 15 and contact 12 at the edges 100 of said opening and also along the entire flat surface of the tongue 16.

The other spring contact 13 has a laterally extending wing 18 seated in a depression at one side of the end of the body, and 105 held therein by the screw cap or shell 2, which is sleeved over the end of the body member and has a non-circular opening in its end to receive a non-circular portion of the body to prevent relative rotation there- 110

between, as will be readily understood. Surrounding the member 15 is an annular conical button 19, of non-conducting material, which is placed in the position shown in Fig. 1 after putting the contacts 12 and 13 and the screw shell 2 on the body member. A washer 20 is then placed on the outside of the button 19 and the end of the rod 15 is upset or riveted to form a head 21, which firmly attaches all of the parts to the body member 1.

The contact members 12 and 13 extend longitudinally of the body in the openings 6 and 7 and are preferably bent into channel form to provide side flanges 22. Near the free ends of said members the side flanges 22 are sheared away from the flat body portions of the contact members, and are bent slightly inwardly, as shown at 22^a in Figs. 7 and 9, so as to engage with the stationary terminals 4 and 5 and guide them to proper position. The contacts 12 and 13 are also punched out intermediate their ends to provide locking projections 23 having abrupt shoulders 24. When the terminals 4 and 5 reach final position these projections spring into openings 25 in said terminals and positively lock the cap and shell and prevent accidental separation thereof.

Each corner of the channel shaped portion of the contacts 12 and 13 is bent or pressed inwardly, as at 26, to form two rounded knobs or projections on each contact.

The cap and shell are assembled in the usual manner by pushing the stationary terminals 4 and 5 into the openings 6 and 7 until locking engagement with the spring contacts 12 and 13 is effected. To disengage the cap and shell, one of said members, such as the cap, is rotated slightly with reference to the other, or to the position shown in Figs. 3 and 4. This twisting movement forces the free ends of the contacts 12 and 13 inwardly, both by the approach of said terminals toward a longitudinal plane between the spring contacts, and also by the engagement of the edges of the terminals with the knobs or projections 26. The in-

ward movement of the contacts 12 and 13 50 frees the locking projections thereon from the openings in the terminals 4 and 5, enabling the cap to be readily uncoupled or pulled away from the body member.

The construction described is very simple 55 and provides a firm locking connection between the cap and body and also enables said members to be easily disconnected from each other by a simple movement whenever desired.

What I claim is:—

1. An attachment plug, comprising a cap member and a body member, rigid terminals having holes therein carried by the cap and extending into recesses in the base, and co-operating spring contacts having projections in the base, said terminals and contacts being adapted to lock by relative longitudinal movement and to unlock by relative rotative movement about the axis of the plug. 70

2. An attachment plug, comprising a cap member and a body member, blade terminals carried by the cap member having indentations therein, and contacts housed in co-operating recesses in the base, said contacts being provided with abrupt rearward projections adapted to engage the indentations of the terminal blades to normally prevent separation of the cap and body members except by a relative rotative movement 75 about the axis of the plug. 80

3. A separable attachment plug, comprising a cap and base, terminal blade members carried by the cap and extending into recesses in the base, spring contact members in 85 the recesses of the base with beveled raised lugs having abrupt back edges adapted to engage holes in the terminal blades, and beveled lugs at the edges of the contact members adapted to ride on the terminal 90 blade members upon relative rotation of the cap and shell.

In testimony whereof I have hereunto set my hand.

JOHN J. KENNEY.
